[57] CLAIM

The ornamental design for a portable labeling machine,
as shown and described.

DESCRIPTION

FIG. 1 is a top plan view of a portable labeling machine
showing my new design;

FIG. 2 is a right side elevational view of the labeling
machine;

FIG. 3 is a bottom plan view of the labeling machine;
FIG. 4 is a left side elevational view of the labeling
machine;

FIG. 5 is a rear elevational view, from the right in FIG.
2, of the labeling machine;

FIG. 6 is a front elevational view of the labeling
machine;

FIG. 7 is a top perspective view from the left side of the
labeling machine;

FIG. 8 is a top perspective view from the right side of
the labeling machine; and

FIG. 9 is a bottom perspective view of the labeling
machine.

The characteristic feature of my design resides in the
beaded side panels.
